UNITED STATES PATENT OFFICE

CHARLES B. BLAKE, OF PELHAM, NEW YORK, ASSIGNOR TO TIFFANY & COMPANY, OF NEW YORK, N. Y., A CORPORATION OF NEW YORK

DESIGN FOR A SPOON OR ANALOGOUS ARTICLE

Application filed January 15, 1931. Serial No. 38,310. Term of patent 14 years.

To all whom it may concern:

Be it known that I, CHARLES B. BLAKE, a citizen of the United States, residing at No. 206 Ancon Avenue, Pelham, New York, have invented a new, original, and ornamental Design for a Spoon or Analogous Article, of which the following is a specification, reference being had to the accompanying drawing, forming a part hereof.

Figure 1 is a front view of the spoon or analogous article showing my new design.

Figure 2 is a side view.

Figure 3 is a view of the back.

Figure 4 is a cross section on line A—A of Figure 1.

Figure 5 is a cross section on line B—B of Figure 1.

I regard the dominant feature of my design as being in the contour and ornamentation of the handle thereof.

I claim:

The ornamental design for a spoon or analogous article as shown and described.

CHARLES B. BLAKE.
